C. A. WOODBURY,

METHOD OF CHARGING CONTAINERS WITH HIGH EXPLOSIVES.

APPLICATION FILED MAY 23, 1918.

1,329,566.

Patented Feb. 3, 1920.

Pringle Wright & Mull.

UNITED STATES PATENT OFFICE.

CLIFFORD A. WOODBURY, OF MIDDLETOWN TOWNSHIP, DELAWARE COUNTY, PENNSYLVANIA, ASSIGNOR TO E. I. DU PONT DE NEMOURS & COMPANY, OF WILMINGTON, DELAWARE, A CORPORATION OF DELAWARE.

METHOD OF CHARGING CONTAINERS WITH HIGH EXPLOSIVES.

1,329,566.

Specification of Letters Patent.

Patented Feb. 3, 1920.

Original application filed August 4, 1917, Serial No. 184,491. Divided and this application filed May 23, 1918. Serial No. 236,098.

To all whom it may concern:

Be it known that I, CLIFFORD A. WOODBURY, of Middletown township, in the county of Delaware and in the State of Pennsylvania, have invented a certain new and useful Improvement in Methods of Charging Containers with High Explosives, and do hereby declare that the following is a full, clear, and exact description thereof.

0 This invention relates to a process of charging containers intended to be exploded, such as shells, grenades, torpedoes, etc., with high explosives.

5 One object of the invention is to provide a process of charging containers with an explosive which will render new sources of raw materials available for high explosive purposes.

Another object of the invention is to provide a process by which an explosive charge may be cast into a container and there caused to solidify and completely fill the space provided for the charge.

With this and other objects in view the invention consists in the improved process of charging containers with high explosives hereinafter described and set forth in the claims.

The present invention constitutes a division of my original application, Serial Number 184,491, filed August 4, 1917, for bursting charge for containers intended to be exploded.

In the accompanying drawing the figure is an axial section of a shell containing a bursting charge embodying my invention.

The invention is capable of being carried out in different ways, but for the purpose of illustration only one form of the invention will be described herein. In filling containers intended to be exploded, such as shells, grenades, torpedoes, mines, etc., with bursting charges, it is desirable to introduce the largest possible charge into a given space, so as to produce the maximum bursting effect. Trinitrotoluol has heretofore been used to a very large extent, because, among other reasons, it has a relatively low melting point and is therefore easily melted and can be kept melted while being introduced into the shell or other body and does not freeze or

solidify until it has reached the final condition in which it is to remain. The supply of trinitrotoluol, however, may not be adequate, and it is very desirable to render other materials available to replace the trinitrotoluol in whole or in part. I have discovered a new bursting charge for the said purpose, which is of high power; is safe for the purpose; and which bursting charge, though useful and available when introduced into the shell or other container in solid condition, has ingredients having melting points too high to permit such ingredients as a practical matter to be melted and cast into the shell. I have, therefore, invented a process by which the said ingredients can, in effect, become part of a molten mass of such low melting point as to be capable of being successfully cast into a shell and which charge has such qualities that it is solidified; is highly explosive, and is easily detonated; and yet is relatively safe under all ordinary conditions other than detonation.

The trinitrotoluol used in my bursting charge may be either a crude product, such as obtained by direct nitration of toluol, or a product obtained by refining the crude product.

80 My new bursting charge consists of a mixture of trinitrotoluol and picric acid, to which mixture may be added, if desired, trinitroxylen. The preparation of the trinitroxylen is preferably so controlled as to produce a solid, finely divided product.

This bursting charge can be detonated by standard fuses or primers at present in use in shells and projectiles and has an explosive force substantially equal to that of trinitrotoluol.

90 In charging a shell, the ingredients may be pressed into the shell in a dry condition making a compact charge which is readily detonated by the usual primer. It is desirable, however, as above stated, to cast the charge into the shell in order to get the maximum possible weight of explosive into the shell. The picric acid and the trinitroxylen, having melting points too high to permit them to be cast under commercial 100 conditions, I have, as stated, invented a

process by which the said ingredients can, in effect, become part of a molten mass of such low melting point as to be capable of being cast into a shell.

- 5 The trinitrotoluol is melted and the desired quantity of picric acid added, keeping the temperature well above the freezing point of the mixture. I believe the picric acid virtually goes into solution with the 10 melted trinitrotoluol, producing a homogeneous liquid, although I do not wish to be bound by this expression of opinion. At temperatures of from 80° to 90° C. approximately 50 parts of picric acid can be added 15 to 50 parts of trinitrotoluol before a point is reached where no further picric acid will dissolve in the melted trinitrotoluol.

To the mixture thus obtained may then be added either picric acid or trinitroxylen 20 or both substances, keeping the temperature of the mixture well above its freezing point.

In case of adding further picric acid the amount that can be added can be varied 25 within wide limits without seriously affecting the casting properties. This additional picric acid I believe to remain in suspension in the liquid mixture of picric acid and trinitrotoluol. I have found that a mixture 30 of 25% trinitrotoluol and 75% picric acid can readily be cast into a shell or other container.

On adding the trinitroxylen to the mixture of trinitrotoluol and picric acid, I believe 35 the explosive is carried in suspension in the liquid mixture of trinitrotoluol and picric acid. The percentage of any one of the ingredients that may be added to the liquid mixture will necessarily vary, depending 40 upon the fineness of the explosive and somewhat upon the temperature at which the mixing is carried on.

The following formulæ are typical of mixtures that can be used satisfactorily:

- 45 25% to 50% of trinitrotoluol.
75% to 50% of picric acid.
20% trinitrotoluol.
20% picric acid.
50 60% trinitroxytol.
33 1/3% trinitrotoluol.
33 1/3% picric acid.
33 1/3% trinitroxytol.
55 25% trinitrotoluol.
50% picric acid.
25% trinitroxytol.
50% trinitrotoluol.
60 25% picric acid.
25% trinitroxytol.

In the figure of the accompanying drawing I have shown, more or less diagrammatically, a shell body 1 having within it a bursting charge 2, such as I have described, and

having a detonating fuse 3 containing a detonator for detonating the bursting charge.

By the term "container" as used in the claims is meant a container intended to be exploded, such as a shell, grenade, torpedo, mine, etc.

The preferred form of the invention having been thus described, what is claimed as new is:

1. The process of charging an explosive 75 container with trinitrotoluol, picric acid and trinitroxylen, comprising melting trinitrotoluol, dissolving picric acid in the trinitrotoluol, dissolving trinitroxylen in the trinitrotoluol-picric-acid solution while maintaining the temperature of the mixture above the melting point of trinitrotoluol, and pouring the liquid mixture into the container. 80

2. The process of charging an explosive 8 container with trinitrotoluol, picric acid and trinitroxylen, comprising melting trinitrotoluol, dissolving picric acid in the trinitrotoluol, introducing trinitroxylen into said solution while maintaining the temperature of the solution below the melting point of picric acid, and pouring the liquid mixture into the container. 9

3. The process of charging an explosive 9 container with trinitrotoluol, picric acid and trinitroxylen, comprising melting trinitrotoluol, dissolving picric acid in the trinitrotoluol, holding in suspension an excess of picric acid in the trinitrotoluol-picric-acid solution, adding trinitroxylen to said solution, and pouring the liquid mixture into the container. 10

4. The process of charging an explosive container with trinitrotoluol, picric acid and trinitroxylen, comprising melting trinitrotoluol, dissolving picric acid in the trinitrotoluol, introducing trinitroxylen in the trinitrotoluol-picric-acid solution, holding an excess of trinitroxylen in suspension in said solution, and pouring the liquid mixture into the container. 11

5. The process of charging an explosive container with trinitrotoluol, picric acid and trinitroxylen, comprising melting trinitrotoluol, dissolving picric acid in the trinitrotoluol, introducing trinitroxylen in the trinitrotoluol-picric-acid solution, holding an excess of picric acid and trinitroxylen in suspension in said solution, and pouring the liquid mixture into the container. 12

6. The process of charging an explosive container with trinitrotoluol, picric acid and trinitroxylen, comprising melting trinitrotoluol, dissolving picric acid in the trinitrotoluol, introducing trinitroxylen in the trinitrotoluol-picric-acid solution, holding in suspension in said solution an excess of picric acid, and pouring the liquid mixture into the container. 13

7. The process of preparing an explosive

which comprises dissolving picric acid in trinitrotoluol and holding trinitroxylen in suspension in said solution while maintaining the temperature of the liquid mixture below the melting point of picric acid.

8. The process of preparing an explosive which comprises melting trinitrotoluol, adding a quantity of picric acid in excess of the amount soluble in the trinitrotoluol, and introducing trinitroxylen into the liquid mixture while maintaining the temperature of said mixture below the melting point of picric acid.

9. The process of preparing an explosive which comprises melting trinitrotoluol, adding a quantity of picric acid greater than 50% of the amount of trinitrotoluol, and introducing trinitroxylen into the liquid mixture while maintaining the temperature

of said mixture below the melting point of 20 picric acid.

10. The process of preparing an explosive which comprises melting trinitrotoluol, adding a quantity of picric acid greater than 50% of the amount of trinitrotoluol, and adding a quantity of trinitroxylen greater than 10% of the mount of trinitrotoluol while maintaining the temperature of the liquid mixture above the melting point of trinitrotoluol and below the melting point 30 of picric acid.

In testimony that I claim the foregoing I have hereunto set my hand.
